CLAIM

The ornamental design for a smart card interface, as shown and described.

DESCRIPTION

FIG. 1 is a perspective view of a smart card interface; FIG. 2 is a top view thereof; and, FIG. 3 is an enlarged top view thereof. The illustrative broken line showing of a base surface throughout the drawing figures depicts an exemplary component to which the smart card interface might be applied and forms no part of the claimed design.

1 Claim, 2 Drawing Sheets

Related U.S. Application Data
